SPARKING TARGET GAME

Everett W. Creswell, Auburn, Mass.

Application April 30, 1936, Serial No. 77,200

1 Claim. (Cl. 273—102.1)

My present invention is a novel and improved 5 sparking target, toy, game, or apparatus, and the object of this invention is to improve and perfect the device and apparatus of my prior and copending application Ser. No. 22,207, filed May 18, 1935.

In my said prior target game, I illustrated therein and have claimed broadly a device which would have a target operated on the striking of 10 a missile to produce a sparking effect, or a series of sparks, or the like. In my present device I have improved the spark-creating apparatus, the target and releasing means, and have rendered the same more positive in action upon the striking 15 of the missiles, or contact with a stick, wand, or the hand of a player; and have developed means permitting a winding up of the spring and temporary release of same so that a large number, or a plurality of successive operations can be 20 performed without a rewinding; whereas in my prior device the movable part of the target had to be reset each time.

In my present invention, therefore, I have both 25 improved and simplified the apparatus and have provided automatic means for continuous resetting of the target or movable member, together with automatic means for insuring a continuous sparking effect for a predetermined length of time, whereupon the target will again be ready 30 for instant use without attention from the player, resetting, rewinding, or the like.

In carrying out the present invention I prefer 35 to utilize a movable target which will, upon being struck by a missile, or other object, instantly release the spark-creating mechanism without displacing the target from its relative position, so that the apparatus is at all times in desirable 40 operative position. I am enabled to secure a suitable release of the spark-creating mechanism by a slight oscillating movement of the target as distinguished from the complete release and rotation as illustrated in the embodiment of the apparatus in my said prior application.

Furthermore, I may arrange or adjust the 45 sparking instrumentalities to produce any desired or predetermined series and sequence, in time or number of sparking effects, or the like; and I accomplish this in a simple and efficient manner by suitably timing the stubs or other adjusting means during the unwinding of the spring 50 actuating the mechanism.

Also in the present embodiment of the invention I prefer to utilize one or more centrifugally 55 operated spark-creating devices independent of the target before release by the same instead of

having the target itself rotate and produce the sparking effects.

Referring to the drawings illustrating preferred embodiments:

Fig. 1 illustrates an air pistol, or the like, which 5 may be utilized as part of the game and as the missile-throwing device against the target;

Fig. 2 is a diagrammatic view illustrating the position of the apparatus;

Fig. 3 is an enlarged cross-sectional view of 10 one form of the target apparatus;

Fig. 4 being a plan view on the line 4—4 of Fig. 3;

Fig. 5 is an enlarged fragmentary plan view 15 illustrating a typical form and contour of the movable target device;

Fig. 6 is an enlarged cross-sectional view of a modified form of driving mechanism;

Fig. 7 is a view illustrating the target in use 20 with the spark-creating instrumentalities in operation;

Fig. 8 is a plan view on the line 8—8 of Fig. 6, and

Fig. 9 is a fragmentary plan view on the line 25 9—9 of Fig. 6.

As shown in the drawings any type or sort of missile or missile-throwing device may be utilized. I have illustrated for this purpose a well-known type of air gun 1 with a contact missile 2, which may be of the vacuum cup type, if desired, in 30 order that it will stick on the target center when it strikes the same and remain to show the position of contact.

This, however, is entirely optional as the target apparatus is so constructed and arranged that 35 any striking by a missile or otherwise of the surface of the target will release the sparking mechanism and thus register the hit on the movable center 3. The target apparatus comprises a supporting plate 5 which carries the apparatus, 40 and which may be suspended, supported, or secured to a post, wall, or the like when in use. In the form shown in Figs. 3 and 4, suitably secured to the plate 5, is a frame 6, and attached to the latter frame is a flanged second frame 7 secured 45 by rivets 8—8 (see Fig. 3), which frame 7 in turn carries a further frame 9 in which are suitably mounted a winding spring 10 and a driving train comprising gear 11, pinion 12, driving a second 50 gear 13 in mesh with a pinion 14 which is secured to the shaft 15, having at one end a block 16 carrying one or more freely pivoted arms 17—17, which are adapted to rotate at relatively high speed upon release of the spring 10 thru the 55

increased gear and pinion construction shown and described.

The arms 17-17 are attached to a rotatable block 16 near the lower portion of same, and at the end of each block is a projecting plug 18 of flint, adapted to contact with and slide over the surface of a strip of emery paper 20, or the like, so that when the shaft 15 is rotated by the release of the spring 10, the arms 17 will be thrown out horizontally owing to centrifugal force, and the contact members 18-18 will produce a contact with and striking effect on the emery paper 20, as the same are rapidly rotated therethrough.

A key 21 secured to the stem 22 is provided to wind the spring 10 in the usual manner. Secured to the gear 11 to which is attached the spring 10 is an overhanging frame 25 in which one end of the spring 10 may be secured, as shown at 26, with the inner end attached to the shaft 22 for winding the same. On top of the frame 25 is a stop 28 against which a flat spring 30 will normally bear, said spring 30 having its rigid end 31 fitted thru a slot 32 in an end slot of the frame 9 and adapted to span the shaft 15 and be normally in contact with the hub of the pinion 14 on said shaft. A washer or boss 32 may be fitted for the purpose of this bearing.

A coil spring 33 extending around the axle of the pinion 12 and bearing between the under side of the top frame 9 and the adjacent portion of the flat spring 30, as clearly shown in Fig. 3, is also provided. The shaft 15 is arranged to be reciprocated by the striking of the surface of the target 3, whereupon the flat spring 30 is released against the tension of the spring 33 and releases the stop 28 on top of each frame 25; whereupon the spring 10, which has been wound to desired tension, is released and the gear 11 rotated thru one revolution until the stop 28 again strikes on the spring 30, the momentary impact on the target compressing the spring 33 during the momentary time of impact, whereupon the coiled spring 33 will force back the flat spring 30 on top of the frame 25, the stop 28 having meanwhile passed under the same during the initiation of the unwinding of the spring 10.

In order to have the target 3 perform this release, I mount the same on a pair of movable studs 35-35 securing the ends of said studs thru appropriate recesses in the frame 6, with nuts or heads 36-36 thereon, and with each stud 35 surrounded by a coiled spring 39, as clearly shown in Fig. 3, so that the target normally is raised above the surface of the plate 5 and held yieldingly in position. A center stud 40 on the target 3 is positioned to contact with the head 41 of the shaft 15. Consequently when the face of the target 3 is struck, the springs 39-39 will yield permitting the target 3 to be depressed, with the contact member 40 moving the shaft 15 and, consequently, lifting the flat spring 30 from its holding action against the stop 28, hence permitting a single revolution of the train of gears and consequent actuation of the arms 17, and throwing the same against the emery strip 20 to effect the sparking action. The plate 5 is cut away as shown at 42 to facilitate this oscillating movement and to permit the block 16 on the shaft 15 to be moved in this particular form of the invention.

Referring to the somewhat modified form in Figs. 6, 7, 8, and 9, I have herein illustrated the target 30 mounted on sliding posts 44-44 fitted

thru corresponding recesses directly in the plate 5 and with coiled springs 45-45 surrounding the same and bearing between the under part of the target 3 and the face of the plate 5, washers 46-46 secured to the shafts 45-45 limiting the upward movement of these shafts and also of the target 3, as will be appreciated.

In this modified form of the invention I have illustrated a somewhat different stop on the train of gears when the same are released and the spring 10 unwinding. In this form I apply the train of gears on suitable shafts between the auxiliary frames 48 and 49 and form the shaft 50 carrying the pinion 14 with a projecting end 51 adapted to bear against a movable locking U-shaped member 52, which member has one arm 53 adapted to slide in recesses in the frames 49 and 48, and with the other arm 55 somewhat shorter and adapted to engage in slots 56, 57, or 58 which are formed in the gear wheel 60, corresponding to the gear 13 in the first form, and operating to drive the pinion 14 from the spring 10. A leaf spring 61 attached to the upper part of the frame 49 is positioned to bear upon the U-shaped member 52 and normally impel the same downwardly or to the left, viewed in Figs. 6 and 7.

When the target 3 is struck the same is momentarily pressed downwardly against the tension of the springs 44, depressing the shaft 50, lifting the U-shaped member 52 against the tension of the spring 61, and thus withdrawing the short arm 55 from engagement with one of the slots 56, 57, or 58 in which it normally rests to hold the train of gears from rotating. The parts would thus be shown in the position shown in Fig. 7, and the spring 10 instantly acts to rotate the train of gears and, hence, moves the gears 60 beyond the partition adjacent the slot in which the short arm 55 has previously rested, permitting it to engage the next slot as the target 3 is returned to normal position by the impelling action of the posts 44, and the U-shaped member 55 also returned to position by the impelling action of the spring 61.

The slots 56, 57, and 58 may be of any desired length to give a predetermined sparking action during the operation of the device. In this particular form I have illustrated a pair of arms 66-66 each pivoted, respectively, at 67-67 between a pair of depending ears on a plate 68 secured to the shaft 50 and rotatable therewith. The emery paper 20 is fitted to the base 1 in a path to be struck and contacted with the flint plugs 18-18 in the end of each arm 66 in a manner similar to that described with the pivoted arms 17-17 in the form above described so that rapid rotative motion imparted thereto will throw the arms 66 outwardly and force the flint plugs 18 in contact with the surface of the emery paper 20 as the arms are rotated during the unwinding action of the spring 10.

In Fig. 9, I have illustrated a typical form of locking device for the spring 10 comprising a locking member 70 secured to the winding shaft 71 carrying the spring 10 in this form, slidably secured on a squared end portion of the winding shaft and adapted to engage stops 72, 73, and 74 around the periphery of the line of travel of the locking member 70 on the plate 48, and normally held in downward or locking position by a coiled spring 75. The stops 72, 73, and 74 are arranged with bevelled faces 71 in the line of winding action to permit the members 70 to ride up over the same during the winding of the spring 10 by rotation of the han-

dle 21, whereupon the spring 11 will force the member 10 downwardly in flat contact with the plate 48 and abut against the perpendicular face of the respective stock over which it may have thus ridden to catch and hold the spring against unwinding. Any other convenient or feasible method may be employed if desired.

In both forms of my invention I thus provide automatic resetting means to hold the target 10 in position for a succeeding impact and to provide for a predetermined sparking interval and action. Also I may, and preferably do, form the face of the target 3 with a plurality of recesses or openings 80 to facilitate the visualization 15 of the sparking produced by the rotating flint plugs 18 on the emery 20. These openings may be of any desired design and, if desired, may be covered with colored transparent members, thus producing an attractive kaleidoscopic 20 effect.

The centrifugal action on the arms 17-17 or 66-66 insures a yielding sliding contact between the plates, plugs, and the emery paper to produce an active sparking effect and yet no undue 25 wear, the centrifugal action automatically com-

pensating for wear in the plugs or emery paper, and insuring a proper contact at all times during the unwinding of the spring 10 and the operation of the apparatus for a predetermined time desired.

I claim:

Game apparatus of the kind described comprising a target member of substantial area facing the player, yielding means normally supporting said target in extended position but permitting a limited reciprocating movement of the target when its surface is struck by a missile or the like,—a gear under tension by a windable spring and normally locked against movement,—means automatically unlocking said gear upon reciprocation of the target permitting a limited extent of travel of said gear and thereupon automatically again locking the same while still under driving tension of said spring, in combination with devices associated therewith and actuated by the movement of said gear, to produce a sparking or the like action, while said gear is in motion.

EVERETT W. CRESWELL.
